ATTORNEY.

UNITED STATES PATENT OFFICE

KIICHIRO TOYODA, OF TOKYO, JAPAN

BUFFING DEVICE IN POWER LOOMS

Application filed December 24, 1929. Serial No. 416,274.

My invention relates to power looms provided with a side lever picking motion and is more especially concerned with the picking mechanism of such looms, and the object 5 of my invention is to provide a buffer arrangement for the picking sticks so as to assist the action of the buffer straps which at times are not sufficient to check the motion of the shuttle or the stick receiving the 10 shuttle. The shuttle is apt to move further than is desired, because of a rebound movement of the picking stick, due to the reaction of the side lever, which as the top of the picking stick is hit by the shuttle, is given 15 an upward kick by the shoe provided at the lower end of the stick. This occurs especially in looms running at high speed. Now, the present invention aims to cure this defect and to prevent the shuttle from being 20 knocked back. To this end, I provide a train of friction rollers over which passes a band or strap, one end of which is attached to the end of the side lever, while the other end is attached to the rotatable end roller 25 equipped with a spring controlling the rotation of said roller.

In the appended drawing, on which I have shown an embodiment of my invention, Fig. 1 is a side elevation showing a portion of 30 the loom frame; Fig. 2 is a view at right angles thereto as seen from the right in Fig. 1; Figs. 3 and 4 show respectively in side elevation and in plan view the train of friction rollers, drawn to a larger scale.

On the drawing, 1 indicates a portion of 35 the frame of a power loom; 2 is a bracket secured to the frame and carrying a pivot pin 3, whereby the side-lever shown at 4 is pivotally mounted on the frame. Said lever 40 has secured thereto a picking nose 5 adapted to be engaged by a roller 6 attached to the periphery of a disc 7 which is secured to the tappet shaft 8. At 9 is shown the rocking shaft on which is mounted the slay (not shown). 11 is the picking stick carrying at 45 its lower end the shoe 10. At 12 is shown the spring controlling the picking stick.

Secured to the loom frame 1 is a bracket 50 50, on which are provided a roller 14 and two friction disks 15 and 16, the roller 14 being

rotatable, while the two disks are secured to said bracket. With roller 14 cooperates a helical spring shown at 17, one end of which spring is connected to a projection A secured to or formed integral with the 55 bracket 13, while the other end of the spring is secured to a portion of roller 14. To the latter, there is also secured at 18 (Fig. 1) a band 19, the other end of which is secured by a screw 20 to the end of the side lever 4. 60

When during the picking motion, the roller 6 on the periphery of disc 7 strikes the nose 5, the side lever 4 is depressed with the result that the band 19 becomes slackened and is wound on roller 14 by spring 17, slipping 65 over the peripheral faces of the disks 15 and 16 to the point "B" on bracket 13 (Fig. 3) when further movement is arrested by a projection C on roller 14 coming in contact with the shoulder B (Fig. 4). The side lever 4, 70 however, still continuing its downward movement, the band 19 becomes slackened.

When the picking motion is completed, the picking stick 11 is pulled back by the 75 spring 12. The shoe 10 at the lower end of the picking stick, due to said back pull, being brought to bear against side lever 4 raises the same with the result that the slack in the band 19 is taken up again.

The shuttle now being thrown into the 80 shuttle box (not shown) from the other side, the picking stick receives a forceful push from its before mentioned position resulting in an upward motion of shoe 10 which thereby exerts an upward kick against the side 85 lever 4. But the upward movement of lever 4 is checked by the friction between the band 19 and the friction disks 15 and 16, as well as by the spring 17. Gradually, the band 19 is shifted to a point corresponding to the position of the picking stick at its extreme end ready for picking motion. During this time, the side lever 4 is gradually raised, in close contact with the shoe 10 so that all danger 90 of the side lever knocking down the shoe again by its reaction is removed.

The degree of friction between the band 19 and the disks 15 and 16 can be adjusted by the 95 position of the disk 16 which as clearly shown 100

in Fig. 3, is eccentrically mounted. The tension of spring 17 also is adjustable.

I claim:

1. In power looms having a side lever picking motion, the combination with said side lever and the picking stick, of a friction member, a rotatable roller, a band passing around said friction member in frictional engagement therewith having its one end attached to said side lever and its other end to said rotatable roller, a spring arranged to rotate said roller so as to exert a pull on said band thereby producing a resistance to the upward movement of said side lever and to the picking stick when struck by a shuttle, and a stop for said rotatable roller.
2. The combination as specified in claim 1, in which said friction member is eccentrically disposed to thereby adjust the friction between said band and said rollers and thereby the movement of said side lever.

In testimony whereof I affix my signature.

KIICHIRO TOYODA.
